UNITED STATES PATENT OFFICE.

HAROLD W. ANDERSON, OF CHICAGO, ILLINOIS.

JEWELER'S DISPLAY-TRAY.

No. 800,968.

Specification of Letters Patent.

Patented Oct. 3, 1905.

Application filed May 18, 1905. Serial No. 260,919.

To all whom it may concern:

Be it known that I, HAROLD W. ANDERSON, a citizen of the United States, residing at Chicago, in the county of Cook and State of Illinois, have invented a new and useful Improvement 5 in Jewelers' Display-Trays, of which the following is a specification.

My invention relates to improvements in jewelers' display-trays intended to be used in 10 show-cases or the like to receive the different articles of jewelry and display them in an attractive manner and at the same time permit the removal from the show-case of a single article or of any one of the trays.

15 I have found that the display-bed of a jeweler's show-case is rendered much more attractive if it appear to be formed of one continuous stretch of plush or the like provided with jewelry-holding elevations or depressions 20 than where the bed shows itself plainly to be formed of separate removable trays.

25 My object is to provide a construction of tray which when used in connection with others in a show-case, more especially to fill out the bottom of the same, will cause the display-surface of the case to appear to be formed of one continuous stretch of plush or the like, the separate trays or tray-sections being readily removable from and replaceable in the case.

30 I accomplish this object by providing a construction of tray in which the plush or other covering extends over the edges of the tray-frame or is flush therewith, whereby the surfaces of the frame which would otherwise be 35 exposed are concealed.

Referring to the accompanying drawings, Figure 1 is a broken plan view showing in full lines the whole of one tray and by dotted lines three contiguous trays in part, and Fig. 40 2 an enlarged broken sectional view taken at the line 2 in Fig. 1 and viewed in the direction of the arrow.

45 A denotes a tray of my improved construction, shown as being adapted to hold watches. The frame or body B of the tray is of wood, divided into compartments a, separated from each other by the partitions b. The outer walls c of the compartments are about one-half the thickness of the partitions. The top 50 of the tray comprises interfitting removable blocks or sections of uniform size C, those shown being rectangular and each provided

with a shallow pocket d of a shape to receive a particular article of jewelry, such as a watch. The sections are also each provided with a 55 surrounding flange e of about one-half the width of the partitions b and have downwardly-rounded edges. Each of the sections C fits into a compartment a at its lower portion and rests at its flange e upon the partitions and end walls of the tray. The sections C are provided with a covering f, of plush or other suitable attractive material, extending over their upper surfaces and beveled or rounded edges and preferably over the entire surfaces 60 of the sections, as shown in Fig. 2. The sections, as shown, are also each provided with a cushion g, to which the preferably satin covering h on the under side of the sections is attached. By thus providing the sections with the covering, each section closely contacting with the others and completely covering the body or frame of the tray, no uncovered portion of the frame is exposed and the whole is 65 given the appearance of a tufted bed, on which 70 the articles of jewelry rest or to which they are attached. Likewise, by placing a number of trays in a display-case side by side it may be made to appear that the bottom of the case 75 is one continuous bed formed of plush or other 80 covering material, padded and blocked out to take away any appearance of plainness.

By forming the exposed part of the tray of removable blocks or sections any one of the latter may be removed from the case without 85 removing the whole tray.

What I claim as new, and desire to secure by Letters Patent, is—

1. A jeweler's display-tray having a frame portion and a top formed of sections each provided on its upper surface and edges with an ornamental covering, and adapted to fill out said tray and extend over the edges thereof whereby no portion of the frame is exposed to view, for the purpose set forth. 95

2. A jeweler's display-tray having a frame portion divided into compartments, and a top formed of separate interfitting uniform-sized sections each provided on its upper surface and edges with ornamental covering, and adapted to fit into said compartments and hide the tray-frame whereby no portion of the frame is exposed to view, for the purpose set forth. 100

3. A jeweler's display-tray having a frame portion provided with compartments separated from each other by partitions and a top composed of interfitting sections of uniform size, each provided with surrounding flanges and a covering of plush, or the like, said sections fitting into said compartments to pro-

ject at their flanges over said partitions whereby no portion of the frame is exposed to view, for the purpose set forth.

HAROLD W. ANDERSON.
